UNITED STATES PATENT OFFICE.

FRANK B. BRANSON AND ARLEIGH C. NAVÉ, OF PAWNEE, LOUISIANA.

CAR-ROOF.

No. 895,418.

Specification of Letters Patent. Patented Aug. 11, 1908.

Application filed October 1, 1907. Serial No. 395,372.

To all whom it may concern:

Be it known that we, FRANK B. BRANSON and ARLEIGH C. NAVÉ, citizens of the United States, residing at Pawnee, in the parish of Calcasieu and State of Louisiana, have invented certain new and useful Improvements in Car-Roofs; and we do hereby declare the following to be a full, clear, and exact description of the invention, such as will enable others skilled in the art to which it appertains to make and use the same.

Our invention relates to new and useful improvements in roof construction, and more particularly to that class adapted to be used for forming box car roofs, and our object is to provide means for preventing leakage between the sections forming the roof.

A still further object is to prevent the sections forming the roof from warping, and a still further object is to provide means for preventing the nails or the like used in securing the parts of the roof together, from being drawn out by expansion.

Other objects and advantages will be hereinafter referred to and more particularly pointed out in the claims.

In the accompanying drawings which are made a part of this application, Figure 1, is a perspective view of a portion of a roof showing our improved method of constructing the same. Fig. 2, is a transverse sectional view through the section of the roof. Fig. 3, is a sectional view as seen on line 3—3 of Fig. 2, and Fig. 4, is a perspective view of one of the sections employed in constructing the roof.

Referring to the drawings in which similar reference numerals designate corresponding parts throughout the several views, 1 indicates the rafters such as are commonly employed in connection with the roofs of box cars, and 2 indicates sheeting, the strips of sheeting being extended laterally across the rafters and are secured thereto in any preferred manner, said sheeting being employed for supporting our improved form of roofing sections 3.

The upper surfaces of the sections 3 are provided with longitudinally disposed gutters 4, while one edge of the section 3 is provided with a tongue 5, and the opposite edge thereof with a groove 6 so that when the sections are placed together the tongue of one section will enter the groove of the next succeeding section, and in order to render the joints thus formed water-proof the upper

portion of that edge containing the groove 6 is provided with a lip 7, and the upper portion of that edge of the section 3 containing the tongue 5 is removed to form a seat 8 for the lip 7, the inner end of the seat 8 and the free end of the lip 7 being formed at an angle so that a portion of the end wall 9 of the seat 8 will overhang the tapered edge 10 of the lip 7, thereby forming a lock for the edge of the lip and preventing the same from warping. 65 A gutter 11 is also placed in the upper face of the seat 8 so that should the water in any manner pass between the ends of the seat and lip the gutter 11 would catch the water and prevent the same from passing to the 70 interior of the car between the tongue and groove, thereby rendering the joints between the several sections water-proof.

The several sections 3 employed in forming the roof are secured in position on the 75 sheeting by driving nails 12 through the sections and into the sheeting, and owing to the interlocking edges of the sections, said sections may be secured together by placing the nails at the longitudinal center and each end 80 of the sections, there being preferably two rows of nails at the center and each end of the sections, and in order to prevent the nails from being withdrawn by the action of the sun's rays on the roof or in any other manner 85 we provide metallic strips 13 which are of sufficient width to extend over the two rows of nails at the center and ends of the sections, said strips being secured to the sections 3 in any preferred manner as by means of screws 90 14, and as long as the strips are secured in position over the nails, said nails will be held from withdrawing from the roofing sections, thereby firmly holding the roof in position on the sheeting. 95

It will thus be seen that we have provided a very cheap and economical form of roof, and while we have shown and described the same as employed in connection with car roofs it will be fully understood that it may 100 be employed for building roofs of any class. It will further be seen that by providing the gutters water or the like falling on the roof will be readily carried away and that by forming the meeting edges of the sections as 105 shown, a water tight joint is formed, and it will further be seen that the sections forming the roof will be positively held in their respective position and prevented from warping and becoming loosened by placing the 110

metallic strips over the ends of the nails employed for securing the sections to the sheeting.

What we claim is:

- 5 A roof of the type described, embracing rafters having applied thereto sheeting, a plurality of roof-sections each provided in its upper surface with a plurality of longitudinal drain-channels or gutters and at one longitudinal edge with a tongue, said roof section also being stepped from its general upper surface downwardly at a point a short distance inwardly from said tongue and having what may be termed the thread thereof also
- 10 provided with a longitudinal drain-channel or gutter and the riser member thereof forming an "undercut" shoulder, said tread forming the upper surface of said tongue, said roof-section having its opposite longitudinal

edge provided with a groove, also with a lip 20 projecting some distance beyond, and overhanging said groove and having its forward longitudinal edge of a corresponding outline as that of the aforesaid under cut shoulder and its upper surface in the same plane with 25 the general upper surface of said roof-section, means for securing said roof-sections to said sheeting and strips extending over said securing means and in turn secured to said roof sections.

30

In testimony whereof we have signed our names to this specification in the presence of two subscribing witnesses.

FRANK B. BRANSON.
ARLEIGH C. NAVE.
